UNITED STATES PATENT OFFICE.

HAMILTON S. CRABTREE, OF ANNA, ILLINOIS.

WAGON END-GATE.

SPECIFICATION forming part of Letters Patent No. 335,685, dated February 9, 1886.

Application filed December 2, 1885. Serial No. 184,476. (No model.)

To all whom it may concern:

Be it known that I, HAMILTON S. CRABTREE, a citizen of the United States, residing at Anna, in the county of Union and State of Illinois, 5 have invented certain new and useful Improvements in Wagon End-Gates; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention is an improvement in wagon 15 end-gates; and it consists in the construction, combination, and arrangement of the several parts, as hereinafter set forth and claimed.

In the annexed drawings, Figure 1 is a side view of the device. Fig. 2 is an end view of 20 the same, one side of the gate being broken away. Fig. 3 is a vertical sectional view of the gate. Fig. 4 is a side view of the wagon-body with the gate removed, and Fig. 5 is a detail view of the end of the gate.

25 A is the wagon-body. At its lower rear corner it is provided with a guide-support, B, for the end-gate. This guide-support is secured directly to the wagon-body, as shown. It extends slightly beyond the rear end of the wagon- 30 body, and is provided with an inwardly-projected flange, b, along its edge. The support has a lower extension, b', and a continuation of the flange b extends along the lower edge of this extension on the inside. The outer corners 35 of the guide-support are rounded, as shown, the advantage of which will hereinafter appear.

I secure to the end of the wagon-body a keeper-frame, C, which is provided with two keepers, C' C'', as shown. A spring, D, is secured upon the keeper C', and is provided on its inner side with a pin, D', which passes through a perforation in the keeper C', as will be understood, and engages suitable perforations in the side plate of the end-gate, as will 45 be hereinafter explained.

The keeper-frame consists of a vertical portion, c, arranged along the rear edge of the wagon-body, and the quadrangular portion c', which extends forward and downward from 50 the upper end of the vertical position. The end-gate E is provided with the supporting-plates F, which are secured directly to the rear

side of the end-gate, and bent at right angles to pass through the keepers C' C'', as shown in Fig. 1. The portion F' of the supporting-plate 55 is quadrangular in form, as shown, and is provided near its curved edge with a series of perforations, f, which are engaged by the pin D' in the operation of the device. Its lower forward corner is provided with a small ear, f', 60 within which I form the slot f'' in the line of the radius of the quadrant. The main portion F of the supporting-plate has a small portion cut away at its lower edge to fit over the supports B, as shown in Fig. 2. A pin, G, is also 65 provided at the lower edge of this supporting-plate and passes back of the flange b, working between said flange and the wagon-body.

It will be understood that the construction of both sides of the end-gate is the same, while 70 for convenience I have shown and described the improvements as applied to one side only.

The operation of my end-gate will be readily understood. When the several parts are in the position shown in full lines, Fig. 1, the 75 pins G serve as pivots upon which the end-gate may be swung out to the position indicated by the light dotted lines, when the pin D' will engage the slot f''. Upon reference to Fig. 5 it will be seen that the slot f'' lies almost entirely 80 without the plane of the circle described by the perforations f, and it will then be understood that the end-gate will drop to the position indicated by the heavy dotted lines. When the end-gate is in this position, it will be on a level 85 with the floor of the wagon, the advantage of which is manifest. By releasing the pin D' from engagement with the slot f'' and swinging the gate farther outward, it will depend from the supports B, being suspended by the pins 90 G resting on the flanges b. It can be entirely removed by simply sliding the pins G backward on the flanges b. The rounded corners of the supports aid perceptibly in the operation of the device, as will be obvious from the 95 foregoing.

Having thus described my invention, what I claim, and desire to secure by Letters Patent, is—

1. The combination of the end-gate having 100 a quadrangular side plate provided with a series of perforations near its curved edge and a slot in its lower corner in the line of the radius of the said plate, the wagon-body pro-

vided with a keeper-frame having two keepers, within which the quadrangular plate works, and a spring secured on one of the keepers, provided with a pin which engages the perforations in the quadrangular plate, substantially as set forth.

2. The combination of the wagon-body, having guide-supports for the end-gate secured at its lower rear corners, provided with inwardly-projected flanges, and the end-gate provided

with a supporting-plate having pins secured at their lower edges, which rest upon the flanges of the guide-supports, substantially as specified.

In testimony whereof I affix my signature in presence of two witnesses.

HAMILTON S. CRABTREE.
